UNITED STATES PATENT OFFICE.

ALBERT F. BANCROFT, OF WEST NEWTON, MASSACHUSETTS, ASSIGNOR TO BANCROFT WALKER COMPANY, OF SOUTH BOSTON, MASSACHUSETTS, A CORPORATION OF MASSACHUSETTS.

SHOE AND METHOD OF MAKING THE SAME.

Application filed December 15, 1927. Serial No. 240,148.

This invention relates to that type of shoes in which special provision is made to support the metatarsal arch of the foot by providing a raised portion in the bottom at the middle of the ball portion thereof and also to a method by which a particular shoe of this type may be made.

In providing the shoe bottom with special supporting means for the metatarsal arch usually either a pad or filler piece of some description such as a piece of rubber or leather has been placed directly beneath the sock lining, after the shoe has been constructed, or between the inner sole and outer sole during the process of construction, although other methods have been employed. While each of the above specified methods has certain advantages over the other under certain conditions the results secured with either method have not been satisfactory in many instances, primarily because the inserted pad or support has frequently failed to perform its intended function after the shoe has been worn for a short time, as compared with the normal length of time which the shoe would ordinarily be worn. This failure is believed to be due, in many instances, to the fact that the pad, or other metatarsal supporting means is entirely supported by the portion of the shoe bottom directly beneath it, which becomes depressed, so that, while the inner surface of the shoe may be suitably raised, so as to produce the desired effect when the shoe is first worn, subsequent wear results in the gradual depression or sagging of this raised portion until its beneficial effect becomes destroyed. While it is common practice to recess the bottom of the last on which the shoe is made, to provide suitable space for an inserted pad, or raised portion, in the making operation, and various constructions have been produced in an attempt to overcome the defect above referred to, so far as I am aware, effective and satisfactory means for accomplishing this result have not been produced.

Moreover, in the manufacture of shoes of this character, in which a metatarsal arch supporting filler or pad is incorporated in the shoe at the time of its construction, difficulty has been encountered in providing factory methods which will result in the location of the supporting means in the exact position desired, and, when these methods

fail in this respect, the results produced are particularly objectionable.

The objects of my invention are to provide a method of manufacturing shoes whereby metatarsal arch supporting means may be correctly positioned in the shoe, under practically all conditions, without interference with the ordinary factory operations, and which will be particularly advantageous in connection with the manufacture of shoes of the type in which an outer sole, upper and inner sole are directly connected by any suitable fastening means, such as stitches, nails or cement, without the employment of an intermediate welt. Also, to produce a shoe of this type having in its bottom a raised portion arranged to provide a support for the metatarsal arch which will not be primarily dependent on the outersole for holding the supporting means in position and will not sag or become depressed to an appreciable or objectionable extent, by causing excessive pressure on the outersole portion directly beneath it and consequent excessive wear on this portion, so as to permit such depression.

I accomplish these objects in the manner hereinafter described and as illustrated in the accompanying drawings in which:—

Figs. 1 to 5 are plan and edge views of an innersole, illustrating various steps in the method of construction prior to the lasting operation.

Fig. 6 is a detail perspective view of a form of pad or filler piece which is used in this connection.

Fig. 7 is a perspective view of a last which is employed in the process of manufacture.

Fig. 8 is a cross section of the shoe on the last, previous to the sole attaching operation, taken approximately at the line 8—8 of Fig. 4.

Fig. 9 is a longitudinal sectional view thereof.

Fig. 10 is a similar cross sectional view of the shoe subsequent to the sole attaching operation.

The improved method employed in the manufacture of shoes embodying my invention is the same, with certain additions and modifications, as the method disclosed in the U. S. Patent to Ray No. 1,641,782, but, as the additions and modifications are interpolated therein at various points, a general description of the whole operation will be necessary.

A flexible inner sole 10, which is preferably of thin leather reinforced with canvas, is died out to conform exactly to the bottom of the last on which the shoe is to be made, except that, at the ball portion, it is made slightly wider than the last bottom, as indicated in Fig. 1, in which the dotted lines indicate the portions of the outline of the last bottom which do not conform to the outline of the inner sole. A heel reinforce 12, which will preferably be formed from leather board or card board, is also died out to conform to the heel and shank portion of the last bottom, so that the front portion of its shank will be somewhat narrower than the corresponding portion of the innersole, as shown in Figs. 2 and 4. Also, when the inner sole 10 is died out, a small notch 11 is cut in each edge thereof at the ball portion, for a purpose to be explained. The front edge of the reinforce 12 is preferably skived or slightly beveled on its under side, as indicated at 12^a, leaving, however, a front edge of substantial thickness, as shown in Fig. 5, and an indicating notch 13 is also cut in said edge. The reinforce 12 is secured to the under side of the innersole by staples, in coincidence therewith, as indicated in Fig. 2, the front end portion thereof being left free. The primary function of the reinforce is to reinforce the heel part of the innersole, as its stiffening effect on its shank portion is inconsequential, but it is extended to the ball-portion so that it may be terminated without causing unevenness in the sole bottom. In the present instance, it is also utilized as an effective locating means for a filler piece for providing an additional support for the metatarsal arch, as hereinafter described. The particular embodiment of filler piece shown consists of a pad 15, which is preferably made of soft rubber molded in a form to correspond to the extent to which it is desired to raise the inner surface of the shoe bottom beneath the metatarsal arch. Said pad is preferably made in somewhat triangular, or wedge shaped form and is tapered to a thin edge at all points, the side which is uppermost when in the shoe being rounded transversely, and the opposite side being flat and comprising a face 15^a, which extends from the rear or narrower end to a transverse shoulder 15^b, which is located at the widest part of the pad, and a beveled face 15^c which extends from said shoulder to the wider or front end, the thickness of the pad increasing gradually from the smaller, or rear end to the shoulder, and then decreasing more sharply from the shoulder to the front end, the points of greatest thickness thus being at the middle portion of the shoulder 15^b, the height of which is made to correspond to the thickness of the front edge of the reinforce 12. The next step in the process, after the reinforce has been stapled

in position, as shown in Fig. 2, is to insert the tapering portion of the pad 15 between the inner sole and the reinforce, with its rounded side next the sole and its face 15^a engaged with the reinforce, until its shoulder 15^b is engaged with the front edge of the reinforce. The pad is thus positioned longitudinally, and is then positioned transversely by holding its side edge at the end of the shoulder in coincidence with the notch 13 in the reinforce, in which position the pad is secured to the sole by a small staple 16 which will be driven thru the face 15^c into the innersole. 70 75

A rigid inflexible metal shank stiffener 18 is provided, which is similar in all respects to the stiffener illustrated in said prior patent, except that the front rivet therein is located considerably in the rear of the front end. The stiffener is first placed on the middle portion of the sole and positioned longitudinally by holding its front end approximately coincident with the line between the notches 11. The sole and reinforce are then conformed to the curvature of the stiffener, and secured together, a rivet 19 first being driven thru the heel portion, after which the middle portion will be secured by rivet 20 slightly in the rear of the rear end of the pad 15, so that the latter will not be 90 95 engaged by the rivet.

A last 22 is provided, which is of ordinary form except that it has a shallow cavity 23 formed in the middle of the ball portion, and so located that when, in the next operation, 100 the inner sole, fitted as above described, is positioned on the last and secured thereto, the pad 15 will be directly over the cavity. The lasting operation is then performed and, by this operation, the innersole portion directly 105 beneath the pad 15 will be pressed into the last cavity 23 and the adjacent edge portions of the inner sole, which projected slightly beyond the edge of the last, will be drawn in flush therewith. The outersole 24 will then 110 be secured in position, so that the shoe will then be in the condition illustrated in Figs. 8 and 9. The last will then be withdrawn and the soles, reinforce and upper will then be stitched together by stitches 25 passed there- 115 thru adjacent their edges in the usual manner, as indicated in Fig. 10.

By these operations it will be observed that the inner sole will be bent inward, or arched transversely at the points directly over the 120 pad 15, and will be securely attached at its edges by the stitches to the outer sole and to the reinforce, and, as the reinforce will be held flat, transversely, against the under side of the pad, it will act as a stay, thru the medium of the stitches, lasting tacks or other fastening means, to hold the inner sole in its arched position. As this action on the inner- 125 sole might not be sufficient, when the shoe is worn, to hold the latter arched inward at this 130

point, particularly if it is of light weight material, as compared with the outersole, the tendency to crush down the arched or raised portion is additionally resisted by the pad 15, 5 which is, in turn, supported by the metal shank stiffener 18, the front end portion of which is extended beneath the pad nearly to the front end thereof, as shown in Figs. 4 and 10, and as it is practically inflexible, and 10 is rigidly supported at its heel end, after the heel has been attached, as in the dotted line position of Fig. 9, its front end which engages the pad will be rigidly sustained. Consequently, while the stiffener is primarily 15 effective in making the shank part inflexible and in holding the shoe in tread, it also materially assists in supporting the pad against depression.

As a result, pressure on the raised portion 20 of the shoe bottom beneath the metatarsal arch is not transmitted to the outer sole to an extent which is likely to cause material depression of the middle portion of the latter. That is, with the above described construction, 25 substantial depression of the raised portion is practically prevented thruout the life of the shoe, while with other constructions which have been produced, where pressure on the raised portion is principally sustained 30 by the outersole portion directly beneath it, this portion usually becomes depressed to such an extent, after a few weeks wear of the shoe, that all the advantages thereof are destroyed.

35 By means of the above described method and construction, the raised portion in the shoe bottom is exactly located regardless of the length and width of the shoe, the sizes of the parts and locating points thereof being 40 correspondingly arranged, so that uniform results may be secured when the shoes are manufactured by ordinary factory operations and nothing in this regard will be left to the judgment of the operator.

45 The front rivet in the shank stiffener is located in the rear of the raised portion of the innersole, not only to avoid the necessity of driving the rivet thru the rubber pad, which would involve some difficulty, but to avoid a further difficulty, in that the flat head of the 50 rivet would tend to draw downward, or make an indentation in the inner side of the raised portion of the innersole.

It is also to be noted that the shoulder 15^b 55 on the pad not only acts to provide a convenient and accurate locating means for the pad, but, by making the thickness of the front edge of the reinforce and the height of the shoulder correspond to each other, the beveled surfaces on the front end of the reinforce and 60 on the front end of the pad will be practically continuous and the latter surface will meet the surface of the last bottom at or adjacent the line where the shank surface meets the 65 forepart surface, as indicated in Fig. 9, so

that no unevenness, or cross line will be caused in the outersole.

While the reinforce, which will be directly secured at its edges to the adjacent edges of the innersole, after the latter has been arched inward, will thereby be enabled to act effectively as a stay to hold the inner-sole in its transversely arched position, the outer sole will also have a similar effect when directly attached to the inner sole, as shown, even 75 though it may not be held as nearly flat transversely as the reinforce and may be arched outward about the metal stiffener. That is, pressure on the arched portion of the inner sole which would tend to flatten it, or spread 80 it transversely will be resisted by both the reinforce and the outer sole acting thru whatever fastening, or attaching means, is employed, whether they are tacks, nails, stitches or an adhesive. Moreover, the attachment 85 of the edge portions of these parts to be effective in acting as a stay to hold the inner sole in arched position must be direct. That is, the outer sole would not be effective in this particular if the inner sole were connected 90 thereto thru a welt.

While a form of filler piece, or pad is illustrated in which the transverse elements on its upper side are rounded, or convex, and this construction is considered preferable, 95 any formation of pad in which a raised or thickened middle portion is provided on its upper side, the sides of which decline to the opposite side edges, would be effective in this connection and would be considered an equivalent. 100

I claim:

1. A shoe having an inner sole, a reinforce of sheet material secured to the under side thereof and extending from the heel end to the front end of the shank part in coincidence therewith, a flexible filler piece disposed between the front end portion of the reinforce and the sole at the middle thereof, the portion of the reinforce engaged with the filler piece being held approximately flat transversely and the inner sole portion engaged therewith being arched transversely over the filler piece, and means directly securing the edge portions of the inner sole and reinforce together to hold said inner sole portion in its arched position. 110

2. A shoe having an inner sole a reinforce of sheet material on the under side thereof extending from the heel to the front end of the shank part in coincidence therewith, a flexible filler piece engaged with the middle portion of the inner sole, and extending beneath the front portion of the shank part and rear portion of the forepart thereof, said filler piece having its top side formed to decline from its middle portion to each side edge and its bottom side transversely flat, the inner sole being arched transversely over the filler piece 115 according to the thickness thereof, and the 120

front portion of the reinforce being held approximately flat against the under side of the filler piece, and fastening means directly securing together the edge portions of the inner sole and reinforce adjacent said filler piece, to secure the inner sole in said arched position.

3. A shoe having an inner sole, a heel and shank reinforce of sheet material on the under side thereof, extending to the front end of the shank part in coincidence therewith, a filler piece disposed beneath the middle portion of the inner sole and extending thruout the front portion of the shank part and rear portion of the fore part, and having a transverse shoulder on its under side arranged in abutment with the front edge of said reinforce and tapering in thickness from said shoulder to its front end, said inner sole being arched transversely over said filler piece and having its edge portions secured to the edge portions of the reinforce.

4. A shoe having an inner sole, a heel and shank reinforce of sheet material on the under side thereof and extending to the front end of the shank part in coincidence therewith, a filler piece disposed beneath the middle portion of the inner sole and extending thruout the front portion of the shank part and rear portion of the forepart, the upper surface of said piece declining from its middle portion to its side edges and its under surface being flat transversely, and having a transverse shoulder, arranged in abutment with the front edge of said reinforce and tapering in thickness from said shoulder to a thin edge at both ends, the angular relation of the under surface in front of said shoulder to that in the rear thereof corresponding to the angular relation of the shank and forepart of the shoe, and fastening means securing the edge portions of said inner sole and reinforce at each side of said filler piece.

5. A shoe having an inner sole and an outer sole, a filler piece disposed therebetween at the middle portion thereof and extending thruout the ball portion in position to provide a support for the metatarsal arch, the transverse surface elements of said piece declining from the middle portion on its upper side and being approximately horizontal on its under side, and the inner sole being transversely arched thereover and having its surface width at its arch portion increased correspondingly to the extent to which it is arched, so that its adjacent edges coincide with the normal outline of the shoe bottom, and fastening means directly connecting the edge portions of the soles at each side of said filler piece to hold the inner sole in arched position.

6. A shoe having a flexible inner sole and a flexible reinforce on the under side thereof

extending from the heel end to the front end of the shank part, a filler piece disposed beneath the middle portion of the inner sole in position to afford a support for the metatarsal arch of the foot and having its rear portion disposed over the front portion of the reinforce and its front portion extending beyond the front end thereof, an inflexible shank stiffener rigidly held at its heel end and extending beneath and in engagement with said reinforce and the front portion of said filler piece in conformity with the longitudinal formation of the corresponding bottom portion of the shoe, said inner sole being arched transversely over said filler piece and said reinforce being held transversely flat and connected at its edge portions to the edge portions of the inner sole.

7. The method of making shoes which consists in providing a shaped inner sole and a reinforce which corresponds in shape to the heel and shank portion thereof, and providing a filler piece for inwardly bending the inner sole beneath the transverse arch of the foot, positioning the reinforce on the under side of the inner sole in coincident relation therewith and positioning the filler piece between the inner sole and the reinforce in predetermined relation to the front edge of the reinforce laterally and longitudinally of the sole and securing all of said parts together as thus positioned, then securing the inner sole to the last bottom, lasting the upper onto the inner sole and completing the manufacturing operation.

8. The method of making shoes which consists in providing a shaped inner sole and a reinforce which corresponds in shape to the heel and shank portion thereof, and providing a filler piece for inwardly bending the inner sole beneath the transverse arch of the foot, positioning the reinforce on the under side of the inner sole in coincident relation therewith and positioning the filler piece between the inner sole and the reinforce in predetermined relation to the front edge of the reinforce laterally and longitudinally of the sole and securing all of said parts together as thus positioned, then providing a last having a cavity in its bottom in a position corresponding to the inner sole portion engaged by the filler piece, positioning the inner sole as thus prepared on the last bottom, bending said portion thereof into said cavity so that the adjacent edge portions of the inner sole are drawn inward, lasting the shoe and securing said edge portions of the inner sole to the reinforce in their indrawn positions and completing the making operation.

In testimony whereof, I have signed my name to this specification.

ALBERT F. BANCROFT.
